(57) **CLAIM**

The ornamental design for a two-liter bottle handle, as shown and described.

DESCRIPTION

FIG. 1 is a perspective view of a two-liter bottle handle showing my new design;

FIG. 2 is a front elevational view thereof;

FIG. 3 is a rear plan view thereof;

FIG. 4 is a side elevational view, the opposite side being a mirror image thereof;

FIG. 5 is a top plan view thereof; and,

FIG. 6 is a bottom plan view thereof.
